UNITED STATES PATENT OFFICE.

ERWIN R. STOEKLE, OF MILWAUKEE, WISCONSIN.

VARIABLE RESISTANCE.

Application filed April 24, 1923. Serial No. 634,297.

This invention relates to improvements in electrical resistances, particularly of the type employing a resistor that would easily be injured by the usual methods of making a sliding or rubbing contact therewith. In my Patent #1,488,681, dated March 13th, 1923, and in my co-pending application, Serial No. 621,812, filed February 28th, 1923, electrical resistances are described in which the resistance is varied by pressing a metallic contact member into variable contact with the surface of a resistor. The absence of a sliding or rubbing motion of the contact member upon the resistor obviates any abrasion of the resistor which would result from the usual sliding contact. My present application describes new and improved means for effecting a non-rubbing contact between the metallic contact member and the resistor.

One object of my present invention is to provide improved and simplified means for pressing a contact member into controllably variable and intimate contact with a resistor whereby the resistance between the terminals connected to said resistor may be continuously and smoothly varied.

Another object is to provide an improved form of this resistance particularly adapted to be used as a so-called potentiometer resistance in which the resistance between the contact element and the end terminals of the resistor may be controllably varied.

Another object is to provide an improved form of this resistance in which the curve of variation of the resistance with respect to displacement of the operating knob may be made of any desired form.

Another object is to provide a novel construction for accomplishing the above desired results in which the path of the current shall be through a small thickness and relatively large area of the resistor thereby permitting the use of a resistor of relatively high specific resistance.

Other objects and novel features of this invention will be apparent from the following description and the accompanying drawings, Figures 1 to 5.

Figures 1 and 2 show a cross section and plan view respectively of a construction of the device in which the contact member con-

sists of a loose disc which may be inclined into contact with the resistor at a variable location thereon.

Figure 3 shows a cross section of a construction in which the contact member is in the form of a curved rocker whose tangency with the resistor may be changed by means of a screw.

Figures 4 and 5 show two forms of the resistor element and its mounting particularly adapted to the construction of Figure 3.

Referring to Figure 1, the insulating base 1 has mounted upon it the resistor 2, which is connected at its ends to the terminals 3 and 4, shown in Figure 2. The contact disc 5 passes loosely over the shaft 6 and rests upon the shoulder 7 on the threaded mounting bushing 8. The shaft 6 has fastened to it the hub 9 which carries the spring pressure arm 10. The knob 11 serves to rotate the shaft 6 and its associated spring arm. The panel for mounting the device is shown at 12. A metallic connecting strip 13 connects the disc contact member 5 to the terminal 14. A pin 15 passes through a hole in the disc 5 and prevents a sliding motion of the disc upon the resistor as well as serving as a stop to limit the rotation of the arm 10.

The disk 5 for an appreciable distance inwardly of its outer edge is pressed upwardly, as shown in the drawings, to provide a smooth, conical contacting surface adjacent the resistor 2, so that as the arm 10 is revolved over said disk, the said conical surface thereof is rolled over the resistor in tangential engagement therewith, thus varying the resistance in infinitesimal steps.

The operation of the device is as follows:—

Current entering at either terminal 3 or 4 passes through the resistor to the place where the disc 5 is pressed into contact with the resistor by the spring arm 10. At this place the current enters the disc passes through the connecting strip 13 and out at terminal 14. Rotation of the spring arm 10 by means of the knob and shaft changes the location of the contact of the disc 5 upon the resistor and thereby varies the resistance between terminal 14 and the terminals 3 and 4.

Referring to the Figures 3 and 4, the in-

sulating base 16 has mounted upon it the resistor strip 17 which is clamped thereto at its ends by the electrical terminals 18 and 19. The metal plates 20 and 21 extend under 5 and make contact with the lower surface of the resistor strip over an area whose boundaries are shown by the dotted lines in Figure 4. Holes 22 and 23 are cut in both the metal plates and in the resistor to insulate these 10 elements from electrical contact with the threaded shaft 24 and the screw 25.

The curved contact member 26 is held in tangent relation to the resistor by means of the pressure spring 27, the threaded shaft 15 24 and its co-operating nut 28. The shaft 24 passes freely through the mounting bushing 29 and through a slotted hole in the member 26 and may be rotated by means of the operating knob 30. The nut 28 fits in a recess 20 on the upper edge of member 26 thus preventing its rotation. The screw 25 is threaded to the base and passes freely through the washer 31. Connections to the contact member are made at the terminal nuts 32 25 and 33.

The operation of the device is as follows:—

Current entering at either of the terminals 18 or 19 passes along the resistor to its region 30 of tangency with the member 26, and from this member out through the terminal 32. Right handed rotation of the knob and shaft draws down the nut 28, rocks the member 26 and moves the location of its contact with 35 the resistor towards the terminal 19 thereby decreasing the resistance between terminals 19 and 32 and increasing the resistance between terminals 18 and 32. Left handed rotation reverses the above described variations. A resistance of relatively low value 40 is attained when the contact of member 26 is directly over the plates 20 or 21 since in this case the path of the current will be from the plate through the thickness of the resistor strip only.

When it is desired to construct a rheostat of this type which shall have a relatively low resistance the plates which make contact with the under surface of the resistor may 50 have the form and extent indicated by the dotted lines in Figure 5. In this construction the current entering at terminal 34 flows from the plate 35 substantially normal to the plane of the resistor to the curved contact 55 arm, thence back through the thickness of the resistor to the plate 36 and leaves at the terminal 37. A change in the location of tangency of the contact member upon the resistor changes the relative areas of contact and therefore the relative resistances of 60 the paths of the current from the contact member to the respective plates 35 and 36.

In the above described constructions any desired curve of variation of the resistance with respect to displacement of the operat-

ing knob may be obtained by cutting either the resistor strip or the underlying metal plates of the desired shape. It is apparent that when the plates are cut diagonally as shown in Figure 5 the resistance between terminals 34 and 37 remains substantially fixed irrespective of the position of the contact member. The resistance between the contact member and terminal 34 however decreases as the contact moves toward 70 34, whereas for the same movement the resistance between the contact member and terminal 37 increases at the same rate so that the resistance between terminals 34 and 37 75 remains substantially constant. This construction therefore permits of dividing the potential applied between the terminals 34 and 37 into proportionate parts which may be taken off between the contact member terminal and either of the end terminals. 80

It will be observed from the foregoing, that I have provided a curved contact surface engaging a flat resistor in a line extending transversely over the entire exposed conducting surface of the resistor. In Figures 90 1 and 2 of the drawings, this is accomplished by turning up the marginal edge or surface of the disk to form a conically curved surface which makes true linear tangency with the flat resistor and rolls without sliding 95 upon the surface of the resistor as the pressure arm is rotated. In Figure 3 of the drawings, wherein a linearly disposed resistor is employed in lieu of the circularly disposed resistor of Figure 1, the contact member also has a curved surface making a linear tangency with the surface of the flat resistor and is adapted to rock or roll upon said surface. 100

It will be obvious to those skilled in the art that the invention is susceptible of various changes and modifications without departing from the spirit thereof and it is not, therefore, desired to limit or restrict the same, except where limitations appear in the 105 appended claims.

What I claim as new and desire to secure by Letters Patent is:—

1. An electrical resistance comprising an insulating base; a circularly disposed resistor in the form of a flat open ring mounted on the face of said base; suitable terminals for establishing electrical connections with said resistor; a disc shaped contact member placed substantially concentric with respect to said resistor, and having a circumferential conical surface extending adjacent the surface of said resistor; means for preventing a sliding motion of said contact member upon said resistor, and means for inclining the plane of said contact member about a substantially centrally located point, whereby said contact member may be brought into contact with said resistor at a variable location along the latter, thus controllably 110 115 120 125 130

changing the resistance between said contact member and either of the terminals of said resistor.

2. An electric resistance unit comprising a substantially flat resistor having a smooth face of conducting material, terminals therefor, a metallic contact element having a curved surface on one face thereof, said curved surface having transversely extending portions of substantial extent adjacent to and adapted to be engaged with said resistor, and means for rocking said element to effect contact thereof with said resistor at a variable location along the latter.

3. An electrical resistance unit comprising a substantially flat resistor having a smooth electrically conducting surface; terminals for said resistor; a contact element having a curved surface on one face thereof adjacent said conducting surface; said curved surface having transversely extending portions of substantial extent adapted to be engaged with said conducting surface; and means for rocking said contact element into a continuously variable location of contact along said conducting surface to effect a variation of resistance in infinitesimal steps.

4. An electrical resistance unit comprising an insulating base, a flat resistor secured to said base and having a smooth conducting surface; suitable terminals for said resistor; a contact member having a curved surface on one face thereof, adjacent said conducting surface; said curved surface having transversely extending portions of substantial extent adapted to be engaged with said conducting surface; means for preventing a sliding motion of said contact member on said conducting surface, and means for pressing said rolling contact member into firm contact with said conducting surface at a gradually variable location on said conducting surface, whereby the resistance between said contact member and either of said terminals may be varied in infinitesimal steps.

5. A variable electrical resistance unit comprising an insulating base, a resistance element circularly disposed upon said base, said element having a smooth electrically conducting surface; a disc shaped contact member having a substantial surface of one face and adjacent its periphery adapted to be pressed against said conducting surface; said surface of said disc-shaped contact member having transversely extending portions of substantial extent engageable with said conducting surface; means for preventing a sliding motion of said peripheral surface upon said conducting surface; suitable terminals for establishing electrical connections to said contact member and to said resistance element; and means including a rotatable spring pressure arm for pressing said peripheral surface into substantially linear tangency

with said conducting surface at a variable location on the latter; whereby a substantial area of contact between said peripheral surface and said conducting surface is secured; and whereby a variation of resistance between said terminals may be accomplished in infinitesimal steps.

6. A variable electrical resistance unit comprising an insulating base; a resistance element circularly disposed upon said base; said element having a smooth electrically conducting surface; a contact member having a conical surface adjacent said conducting surface of said resistance element, suitable terminals for establishing electrical connections to said contact member and to said resistance elements; means for preventing translation of said conical surface with respect to said conducting surface; and means for effecting a rolling tangential engagement of said conical surface upon said conducting surface whereby the resistance between said terminals may be varied in infinitesimal steps.

7. A variable electrical resistance unit comprising an insulating base, a resistance element mounted upon said base, said resistance element having a smooth flat electrically conducting surface; a disc-shaped rigid contact member having a smooth conical surface near its circumference, said conical surface being adjacent said conducting surface; means for preventing rotation of said contact member; an element connecting said contact member to a terminal; suitable terminals for making electrical connections to the ends of said resistor; a spring pressure arm bearing upon said contact member and adapted to press said conical surface of said contact member into firm contact with the conducting surface of said resistor; a rotatable shaft fastened to said pressure arm and passing substantially through the vertex of the conical surface of said contact member; whereby rotation of said pressure arm by means of said shaft will cause said conical surface of said contact member to roll in a variable location of contact upon said smooth conducting surface of said resistor, thus permitting variation of resistance in infinitesimal steps between the terminal connected to said contact member and the terminals at the ends of said resistor.

8. A contact member of the character described comprising a disc having its marginal edge upturned to form a conical contacting surface, and means for mounting said disc for wobbling movement in operative position in a rheostat.

9. A contact member for rheostats employing annular resistors, said member comprising a disc having a contacting surface of frustrated conical design adapted to have wobbling movement in operative position in a rheostat.

10. An electrical resistance comprising an insulating base; a resistor mounted upon said base; suitable terminals for establishing electrical connections with said resistor; a curved contact member having a convex surface adjacent the surface of said resistor; means for preventing a sliding motion of said contact member upon said resistor; and controllable means for imparting a rocking motion to said contact member upon said resistor, whereby the location of tangency of said contact member upon said resistor may be varied, and the resistance between said contact member and either of said resistor terminals may be varied. 15

In witness whereof, I have hereunto subscribed my name.

ERWIN R. STOEKLE.
